TRAFFIC PROTECTION APPARATUS

Lester E. Spray, Wilkinsburg, Pa., assignor to The
Union Switch & Signal Company, Swissvale,
Pa., a corporation of Pennsylvania

Application February 20, 1947, Serial No. 729,827

6 Claims. (Cl. 246—219)

1

My invention relates to traffic protection apparatus, and particularly to apparatus for providing crossover protection for trains moving along railway tracks which are connected with each other by a crossover track through hand-operated track switches.

A requisite for crossover protection apparatus is that it must be so arranged that a car or locomotive, when occupying a crossover such, for example, as one connecting two main tracks, while the switches are in the normal position for train movements along the main tracks, will cause a signal for each main track to indicate stop if the car or locomotive is within fouling distance of that main track. In crossover protection schemes embodying track circuits, one characteristic should therefore be high shunting sensitivity in order to insure that the crossover track circuits will be shunted if the crossover track has high contact resistance due to infrequency of train movements over the crossover.

One feature of my invention is the provision of means for utilizing one-half of an alternating current wave supplied to a track circuit for energizing a direct current track relay and for utilizing the other half of the wave supplied to this track circuit for energizing a second track circuit through a transformer. With this arrangement the two track circuits, although supplied with energy from the same source, are insulated from each other.

Track circuits arranged in accordance with my invention, to pass half waves of alternating current constituting pulsating unidirectional current, have high shunting sensitivity.

I shall describe one form of apparatus embodying my invention, and shall then point out the novel features thereof in claims.

The accompanying drawing is a diagrammatic view showing one form of apparatus embodying my invention, in which a crossover track is divided into two sections, one of which is supplied with alternating current from a source connected in multiple with a direct current relay, and the other of which is supplied with current from the secondary winding of a transformer, the primary winding of which is connected through an asymmetric unit across the rails of the first track section.

Similar reference characters refer to similar parts in the drawing.

Referring to the drawing, a stretch of railway is shown comprising two main tracks, designated by the reference characters 1T and 2T, inter-

2

connected by a crossover track, designated by the reference character 3T, through hand-operated track switches 1W and 2W. A pair of insulated joints 4 and 5 is provided in each end of track 3T. Joint 4 of each of these pairs is located in the frog side of its end of track 3T between the rails of the adjacent main track, and joint 5 of each pair is located in the other side of the crossover track adjacent the heel of the switch at its end of track 3T. Track 3T is divided into two sections a—b and b—c by a third pair of insulated joints 6 in the rails of this track at an intermediate point between the two pairs of insulated joints 4 and 5.

15 Section a—b is provided with a track circuit including a suitable source of alternating current, shown as a transformer 1F, the primary winding m of which is energized by alternating current from terminals BX and NX, and the secondary winding d of which is connected through impedance 8 and in multiple with a direct current track relay 1XR across the rails of one end of the section, and also including the primary winding m of a second transformer 2F connected through an asymmetric unit 1C across the opposite end of the section.

20 Section b—c is provided with a track circuit including the secondary winding d of transformer 2F connected through an impedance 9 in multiple with a second direct current track relay 2XR across the rails of section b—c adjacent insulated joints 6, and also including a second asymmetric unit 2C connected across the rails of section b—c adjacent the opposite end of the section.

25 35 Each of the asymmetric units 1C and 2C may be of any suitable design such, for example, as the well-known copper oxide half-wave rectifier.

30 Portions of sections of tracks 1T and 2T are shown including switches 1W and 2W, respectively. These sections of tracks 1T and 2T are provided with track circuits including main track relays 1R and 2R, respectively, each connected across the rails adjacent insulated joints 7 at one end of its section.

35 45 A signal 1S is shown for governing traffic movements into the section of track 1T toward the left, as shown in the drawing, which I shall assume is the westbound direction. A second signal 2S is shown for governing traffic movements in the opposite or eastbound direction into the section of track 2T. Signals 1S and 2S may be of any suitable design such, for example, as the semaphore or searchlight type. Signals 1S and 2S are controlled by circuits including con-

tacts of relays 1R and 2R, respectively, and also including contacts of relays 1XR and 2XR.

I shall now describe in detail the circuits and operation of the apparatus shown in the accompanying drawing.

As shown in the drawing, all parts of the apparatus are in the normal condition, that is, each of the switches 1W and 2W is in the normal position for a train movement along main track 1T or 2T, respectively; each of the track relays 1R, 2R, 1XR and 2XR is energized; and each of the signals 1S and 2S is displaying a proceed indication.

In the circuit for section a—b, one-half of the alternating current wave supplied by secondary winding d of transformer 1F passes from secondary winding d, through the winding of relay 1XR, and impedance 8, back to secondary winding d. Current from this half wave is blocked by asymmetric unit 1C from flowing through winding m of transformer 2F. Current from the other half of the alternating current wave passes from secondary winding d of transformer 1F, through impedance 8, rail 3b of section a—b, primary winding m of transformer 2F, asymmetric unit 1C, and rail 3a of section a—b, back to secondary winding d of transformer 1F. The impedance of this path is low compared to that of the winding of relay 1XR, so that very little of this other half of the alternating current wave passes through the winding of relay 1XR.

In the circuit for section b—c, one-half of the alternating current wave from transformer 2F passes from secondary winding d of transformer 2F through the winding of relay 2XR, and impedance 9, back to secondary winding d of transformer 2F. This half wave is blocked by asymmetric unit 2C from passing across the rails of track 3T through unit 2C. The other half of the same alternating current wave passes from secondary winding d of transformer 2F, through impedance 9, rail 3a of section b—c, asymmetric unit 2C, and rail 3b of section b—c, back to secondary winding d of transformer 2F.

As shown in the drawing, contacts 10, 11 and 12 of relays 1XR, 2XR and 1R, respectively, are closed in a circuit for clearing signal 1S. Similarly, contacts 13, 14 and 15 of relays 2XR, 1XR and 2R, respectively, are closed in a circuit for controlling signal 2S.

I shall assume that, with apparatus arranged as shown in the drawing, a trainman reverses switches 1W and 2W for a train to move over track 3T. While a train occupies section a—b, relay 1XR is shunted, causing this relay to be deenergized, and winding m of transformer 2F is also shunted, causing relay 2XR to be deenergized. While a train occupies section b—c, relay 2XR is shunted, causing this relay to be deenergized. When relay 1XR is deenergized, the circuits for signals 1S and 2S will be open at contacts 10 and 14, respectively, of this relay, and, when relay 2XR is deenergized, the circuits for signals 1S and 2S will be open at contacts 11 and 13, respectively, of relay 2XR, causing signals 1S and 2S to display a stop indication.

I shall assume further that, after a train has proceeded over track 3T from one main track to the other, a trainman restores switches 1W and 2W to their normal position, but that a car is left standing on section a—b. Current from transformer 1F is therefore shunted by the train, so that relay 1XR and transformer 2F are deenergized. With transformer 2F deenergized, relay 2XR is also deenergized. Both signals 1S and

2S therefore continue to display a stop indication until the car has been removed from track 3T.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In traffic protection apparatus for a stretch of railway in which two main tracks are interconnected by a crossover track, the combination comprising, a pair of insulated joints in each end of said crossover track one joint of each of said pairs located between the rails of the adjacent main track and the other joint of each of said pairs located in the other side of said crossover track, a third pair of insulated joints at an intermediate point between said first and second pairs of insulated joints for dividing said crossover track into a first and a second section, a transformer having a primary winding connected through an asymmetric unit across the rails of said first section adjacent said third pair of insulated joints and having a secondary winding connected in multiple with a direct current relay across the rails of said second section adjacent said third pair of insulated joints, a second asymmetric unit connected across the opposite end of said second section, a source of alternating current connected in multiple with a second direct current relay across the opposite end of said first section, and traffic governing means for said two main tracks controlled by said first and second direct current relays.

2. In traffic protection apparatus for a stretch of railway in which two main tracks are interconnected by a crossover track, the combination comprising, a pair of insulated joints in each end of said crossover track one joint of each of said pairs located between the rails of the adjacent main track and the other joint of each of said pairs located in the other side of said crossover track, a third pair of insulated joints at an intermediate point between said first and second pairs of insulated joints for dividing said crossover track into a first and a second section, a transformer having a primary winding connected through an asymmetric unit across the rails of said first section adjacent said third pair of insulated joints, a track circuit for said second section including a secondary winding of said transformer and the rails of said second section, a source of alternating current connected in multiple with a direct current relay across the rails of the opposite end of said first section, and traffic governing means for said two main tracks controlled by said direct current relay and by said track circuit for said second section.

3. In combination, a stretch of railway track including a first and a second section, a transformer having a primary winding connected through an asymmetric unit across the rails of said first section, a track circuit for said second section including a secondary winding of said transformer and the rails of said second section, a source of alternating current connected in multiple with a direct current relay across the rails of said first section, and traffic governing means for said stretch of track controlled by said direct current relay and by said track circuit for said second section.

4. In traffic protection apparatus for a stretch of railway track, including a first and a second

section, the combination comprising, a transformer having a primary winding connected through an asymmetric unit across the rails of said first section and having a secondary winding connected in multiple with a direct current relay across the rails of said second section, a second asymmetric unit connected across the rails of said second section, and a source of alternating current connected in multiple with a second direct current relay across the rails of said first section.

5. In combination, a section of railway track, a source of alternating current connected in multiple with a direct current track relay across the rails of one end of said section, a transformer having a primary winding connected through an asymmetric unit across the rails of the other end of said section, and traffic governing means controlled by current from the secondary winding of said transformer and by said track relay.

6. In traffic protection apparatus for a stretch of railway track including a first and a second section, the combination comprising, a transformer having a primary winding connected across the rails of said first section and having a secondary winding connected in multiple with a direct current relay across the rails of said

second section, an asymmetric unit connected in series with said primary winding for passing current from a given rail to the opposite rail of said first section, a second asymmetric unit connected across the rails of said second section for passing current between the rails of said second section in the opposite direction to that in which current is passed by said first asymmetric unit between the rails of said first section, a source of alternating current connected in multiple with a second direct current relay across the rails of said first section, and traffic governing means controlled by said first and second direct current relays.
